UNITED STATES PATENT OFFICE.

GEORGE A. KELLY, OF LONGVIEW, TEXAS, ASSIGNOR TO THE GEORGE A. KELLY PLOW COMPANY, OF LONGVIEW, TEXAS.

DESIGN FOR A PLOW-LANDSIDE.

SPECIFICATION forming part of Design No. 35,389, dated December 3, 1901.

Application filed June 29, 1901. Serial No. 66,614. Term of patent 14 years.

To all whom it may concern:

Be it known that I, GEORGE A. KELLY, a citizen of the United States, residing at Longview, in the county of Gregg and State of Texas, 5 have invented and produced a new and original Design for a Plow-Landside, of which the following is a specification.

The present invention relates to landsides for turning-plows; and the object thereof is to 10 provide a design of this character which is new, original, and useful.

The leading feature of the present design resides in an oblong body-plate that tapers toward one end, the broad end being rounded 15 and the upper corner of the narrow end being cut away and angular. The upper edge of the body-plate is inclined and provided with a pair of notches. These notches have their edges that are nearest the tapered or narrow 20 end of the body-plate disposed at substantially right angles to the upper edge of said plate, and the bottom edges of the notches are also disposed in angular relation to said edges, said bottom edges being furthermore inclined in 25 the same direction as the top edge of the body-plate. Located along the bottom edge of the body-plate, on the opposite sides thereof, are outstanding flanges that taper toward the narrow end of the plate, said flanges also 30 tapering in thickness toward their outer edges. Bolt-holes are formed in the plate and comprise angular sockets that taper to round shank-receiving 35 openings.

In the drawings, Figure 1 is a side elevation 35 of a landside embodying the new design. Fig. 2 is a vertical cross-sectional view through the same.

By referring to the drawings it will be seen

that the landside comprises an oblong body-plate (designated 10) that tapers toward one 40 end, the broad end being rounded and the upper corner of the narrow end being cut away, as at 11, to form the angular front end 12. The upper edge of the plate is inclined, as clearly shown in Fig. 2, and is provided with 45 a pair of notches 13. These notches have their end edges that are nearest the tapered or narrow end 12 disposed at substantially right angles to the upper edge of the bottom plate, and the bottom edges of the notches 50 are in like manner disposed in angular relation to said end edges, whereby angular shoulders 14 are formed. It will furthermore be noted by reference to Fig. 2 that these bottom edges incline in the same direction as the 55 top edge of the body-plate. Bolt-holes 15 are formed in the plate and comprise angular sockets which taper to round shank-receiving openings. Located along the bottom edge of the body, on opposite sides thereof, are projecting flanges 16, which flanges taper toward the narrow end 12 of the body-plate and also taper in thickness toward their outer edges. 60

Having thus described my invention, what I claim as new, and desire to secure by Letters 65 Patent, is—

The design for a plow-landside as herein shown and described.

In testimony that I claim the foregoing as my own I have hereto affixed my signature in 70 the presence of two witnesses.

GEORGE A. KELLY.
